UNITED STATES PATENT OFFICE.

ELIZA A. R. KITCHEN, OF MONROE, OHIO.

DESIGN FOR A VIOLIN-BODY.

SPECIFICATION forming part of Design No. 32,088, dated January 9, 1900.

Application filed December 4, 1899. Serial No. 739,206. Term of patent 14 years.

To all whom it may concern:

Be it known that I, ELIZA A. R. KITCHEN, a citizen of the United States, and a resident of Monroe, in the county of Butler and State of Ohio, have invented and produced a new and original Design for a Violin-Body, of which the following is a full, clear, and exact specification.

Reference is to be had to the accompanying drawings, forming a part of this specification, in which similar characters of reference indicate corresponding parts in both the views.

Figure 1 is a face view of a violin, showing my design; and Fig. 2 is a side view of the same.

The invention relates to stringed and bow-operated musical instruments.

The design in its entirety consists of a body A, appearing at its lower end portion B in heart shape and at its upper portion C in star

shape, and a neck D, extending from the star-shaped portion C and terminating in an anchor-shaped head E.

The leading feature of the design consists of the body, part of which is heart-shaped ²⁵ and part star-shaped; and a minor feature of the design consists of the anchor-shaped head.

Having thus fully described my invention, I claim as new and desire to secure by Letters Patent—

The design for a violin-body, as herein shown and described.

In testimony whereof I have signed my name to this specification in the presence of two subscribing witnesses.

ELIZA A. R. KITCHEN.
